UNITED STATES PATENT OFFICE.

THOMAS SAMPSON, OF WATERVILLE, MAINE.

YARN SPOOL OR BOBBIN.

SPECIFICATION forming part of Letters Patent No. 634,738, dated October 10, 1899.

Application filed May 18, 1899. Serial No. 717,253. (No model.)

To all whom it may concern:

Be it known that I, THOMAS SAMPSON, of Waterville, in the county of Kennebec and State of Maine, have invented an Improvement in Yarn Spools or Bobbins, of which the following description, in connection with the accompanying drawings, is a specification, like letters on the drawings representing like parts.

10 This invention has for its object the production of a novel yarn spool or bobbin. These bobbins or "spools," as they are sometimes called, consist of bodies having projecting journals and heads attached to said bodies, 15 said heads being commonly made of a plurality of thicknesses of material to lessen their liability to break by careless handling. These heads have been attached to the bodies in numerous ways.

20 My invention consists, essentially, in novel means by which to attach the head to the body.

In accordance with my invention I extend 25 through a slot in the body an elongated locking member or bar having two tapped holes, and into these holes, at the opposite ends of the bar, I insert the threaded ends of two headed retaining-bolts, extended first through a cap applied to the face of the head and then 30 through holes in the head and along through longitudinal holes or spaces made in the body.

Figure 1 in section shows an end of a bobbin or spool with my improvements added; and Fig. 2 is a section taken in the dotted 35 line $x-x$; Fig. 1.

The body A of the spool and the head B, shown as composed of two thicknesses of material, are and may be as usual. I bore the body at a substantially diametrically and 40 slot the same to present a quadrangular slot, in which I place a locking member, shown as a bar a' , provided near each end with a tapped hole to receive the threaded ends c of two screws or bolts C. Outside the head I place 45 a cap D, preferably of metal and preferably of concavo-convex shape in cross-section, yet the particular shape of the cap is not material. The screws are inserted through suitable holes in the cap, then through suitable 50 holes b in the head of the spool, and then along in longitudinal grooves or spaces a^3 in

the body, the threaded ends of the screws then entering the holes of the bar a' , which I shall designate as a "locking member" or "double tie-bar or nut." The head fits a reduced part a^4 of the body and is forced against a shoulder a^5 of the body. The bolts occupy a diagonal position relative to the longitudinal axis of the body, which enables the heads of the bolts to act on the head B at a greater 60 distance from the center of rotation of the body, and yet permits the threaded ends of the bolts to occupy a position wholly within the periphery of the body.

By the term "screw" as mentioned in the 65 claims I mean to include any equivalent bolt or device.

Having described my invention, what I claim, and desire to secure by Letters Patent, is—

70 1. In a spool or bobbin, a body having a transverse opening, a double nut located in said opening and adapted at its ends to be engaged by screws, and a head applied to said body, combined with two bolts extended 75 through said head and body in a diagonal line, and in engagement with said nut, the inner ends of the screws being located within the periphery of the body and the heads without said periphery.

80 2. In a spool or bobbin, a body having two diametrically opposite longitudinal grooves, a device carried by the body diametrically thereof, and its opposite ends projecting into the inner ends of the grooves and being 85 threaded, a head fitted upon the outer end of the body and provided with two openings, headed securing devices passing through said openings and in threaded engagement with said threaded ends, the shanks of said devices 90 being disposed diagonally in the two grooves, and a cap fitted against the outer end of the head and held in place by the heads of said headed securing devices.

95 In testimony whereof I have signed my name to this specification in the presence of two subscribing witnesses.

THOMAS SAMPSON.

Witnesses:

JOHN C. EDWARDS,
AUGUSTA E. DEAN.
